ALMON W. COBLEY, OF WILKINSBURG, PENNSYLVANIA, ASSIGNOR TO WESTINGHOUSE ELECTRIC & MANUFACTURING COMPANY, A CORPORATION OF PENNSYLVANIA.

MEANS FOR MINIMIZING INDUCTIVE INTERFERENCE.

1,818,730.

Specification of Letters Patent.

Patented Oct. 14, 1919.

Application filed November 3, 1917. Serial No. 200,035.

To all whom it may concern:

Be it known that I, ALMON W. COBLEY, a citizen of the United States, and a resident of Wilkinsburg, in the county of Allegheny and State of Pennsylvania, have invented a new and useful Improvement in Means for Minimizing Inductive Interference, of which the following is a specification.

10 My invention relates to means for minimizing inductive disturbances that may be impressed by an alternating-current transmission system upon an adjacent electrical circuit, such as an intelligence-transmission circuit.

15 More particularly, my invention relates to means whereby inductive disturbances, arising from the flow of currents in an alternating-current railway system and tending 20 to impair the transmission of intelligence over an adjacent telephone or telegraph circuit, may be substantially minimized.

In U. S. Patent No. 1,196,300, means are shown for confining the return flow of the 25 trolley currents of a railway system to the track rails or in regions of the earth that are closely adjacent to the track rails. In this manner, the zones of disturbing influences arising from the return flow of the 30 power currents are restricted to limited regions relatively close to the trolley conductors where the former may be used effectively to neutralize the disturbances occasioned by the latter. By thus confining the 35 current flow to the track rails, inductive disturbances to which other electrical circuits are subjected, such as intelligence-transmission circuits that are located in proximity to the railway system, may be greatly mini- 40 mized or substantially neutralized.

The system shown in the aforementioned patent contemplates the use of series transformers having primary windings that are connected in series circuit with the trolley 45 conductor and secondary windings that are adapted to connect adjacent track sections in series relationship with one another. In this manner, the trolley conductor and the track rails are inductively interlinked with 50 each other and, by reason of the inherent action of these series transformers, the return flow of the trolley currents is confined to the track rails.

The arrangement mentioned above is, 55 however, ineffective in protecting an adja-

cent electrical circuit, such as a telephone circuit, from inductive disturbances that are generated when a ground develops on one of the feeder mains supplying power to the railway system.

In the system of the present invention, however, I provide means for inductively interlinking the trolley conductor and the track rails whereby the return flow of the power currents will be confined to the track 65 rails, under normal conditions. The feeder mains are likewise inductively interlinked with the track rails in order to preclude the generation of serious inductive disturbances when a ground is imposed upon the feeder 70 circuit.

For a better understanding of the characteristic features of my invention, reference may be had to the following description and the accompanying drawing, the 75 single figure of which is a schematic diagram of a system embodying a form of my invention.

Referring to the figure, feeder mains 1 and 2 parallel a railway system 3 to which power is supplied by means of transformers 4 and 5 that are located at conveniently spaced sub-stations 6 and 6^a, respectively. A power transformer 7 that is located at the generating station supplies high-potential current to the feeders 1 and 2. The secondary winding 8 of the transformer 7 is provided with an intermediate tap 9 that is grounded at 10. The secondary windings 11 and 12 of the transformers 4 and 5 have 90 their corresponding terminals connected to a trolley conductor 13 and track rails 14 of the railway system 3.

The track rails 14 are divided into sections by means of spaced insulating joints 95 15 and are connected to one another by means of metallic bonds 16. A plurality of transformers 17 are inserted at intervals along the railway system, as shown, and comprise primary windings 18 that are connected 100 in series-circuit relationship with the trolley conductor 13 and secondary windings 19 that are connected to the rails 14 through the conducting bonds 16 and across the insulating joints 15.

Other windings 20 and 21 are incorporated in the transformers 17, the former being connected in series-circuit relationship with the feeder main 2 and the latter being similarly connected to the feeder 110

main 1. The windings 18, 19, 20 and 21 of each transformer may be disposed upon a single core member, the windings 20 and 21 being so wound that, under normal conditions, the magnetic fluxes arising therefrom will substantially neutralize each other. This is readily accomplished since the direction of current flow in the main 1 is opposite to the direction of current flow 10 in the main 2, under normal conditions. Similarly, the direction of current flow in the winding 18 is opposite to the direction of current flow in the winding 19.

As a result of inductively interlinking 15 the trolley conductor 13 with the track rails 14, the current flow in the earth will, in general, be for short distances only. The windings 18 and 19 will usually, though not always, comprise substantially equal numbers 20 of turns and, therefore, by reason of the necessity of the ampere turns in the primary winding 18 being nearly equal to the ampere turns in the secondary winding 19, the return flow of the trolley currents will be ordinarily 25 confined to the track rails 14 which are disposed in proximity to the trolley conductor 13. In consequence thereof, the inductive disturbances that may be imposed upon an adjacent circuit 22, shown as a telephone 30 circuit, will be substantially neutralized.

The current flow in the feeder circuit will usually occasion inappreciable disturbances in the telephone circuit 22, since the feeder mains 1 and 2 are thoroughly insulated 35 from ground and the current flow over one is in a direction opposite to that over the other. As a result, the inductive effects arising from the current flow over one of the mains will be neutralized by the inductive effects arising from the oppositely-directed 40 current flow in the other main.

Assumed, for the purpose of illustration only, that a ground 23 is imposed upon the main 1. If the main 1 were not inductively 45 interlinked with the track rails 14 through the transformers 17, the ground currents arising from the grounded connection 23 would seriously interfere with the proper operation of the intelligence-transmission 50 circuit 22. But, since the feeder mains 1 and 2 are severally inductively interlinked with the track rails 14, through the transformers 17, these ground currents are precluded 55 from flowing any appreciable distance through the earth but will, of necessity, traverse the track rails 14.

Because of the return flow of these currents being confined to the track rails 14, in preference to the earth, the inductive disturbances 60 that may be impressed upon the telephone circuit 22 are not of a serious character. Under this condition, the windings 21 serve as primary windings of the series transformers 17 and the windings 19 65 as secondary windings. Therefore, the

series transformers 17 serve to inductively interlink the feeder mains 1 and 2 with the track rails 14 when a ground is imposed on the feeder circuit. Since the several transformer windings 18, 19, 20 and 21 are presumed to have substantially the same number of turns, the current traversing the track rails 14 will be substantially equal to the current traversing the feeder main 1 and the grounded connection 23. The resultant 70 inductive disturbance that may be imposed upon the telephone conductor 22 will therefore be negligible.

While I have shown and described one embodiment only of my invention, it will be 80 understood that many modifications may be made therein without departing from the spirit and scope of the appended claims.

I claim as my invention:

1. The combination with a feeder circuit, 85 and a power circuit one conductor of which is in contact with the earth, of a plurality of spaced transformers for inductively interlinking the conductors of said feeder circuit and the other conductor of the power 90 circuit with said conductor of the power circuit that is in contact with the earth.

2. The combination with a feeder circuit, a railway system comprising a trolley conductor for the transmission of power currents and a track, and means for transferring power currents to the railway system from the feeder circuit, of means for inductively interlinking said track with the trolley conductor and the conductors of said 100 feeder circuit at spaced intervals.

3. The combination with a feeder circuit, and a railway system comprising a trolley conductor for the transmission of power currents and a track, of transformers for 105 inductively interlinking the trolley conductor and the conductors of said feeder circuit with said track at spaced intervals.

4. The combination with a feeder circuit, and a railway system comprising a trolley 110 conductor for the transmission of power currents and a track, of spaced transformers having windings that are severally connected in series circuit with the conductors of said feeder circuit and the railway system in 115 order to inductively interlink the conductors thereof with one another.

5. The combination with an intelligence-transmission conductor, of an electrical distributing system in inductive relation 120 thereto that comprises a feeder circuit having conductors insulated from ground, a power circuit which comprises a conductor insulated from ground and a second conductor in contact with the earth, and inductively interlinking means serving to confine the ground currents from both of said circuits to said second conductor of the power circuit in preference to the earth, whereby the inductive effects impressed upon 130

the said intelligence-transmission conductor may be substantially neutralized.

6. The combination with an intelligence-transmission conductor, of a feeder circuit, 5 a railway circuit, both of which are inductively related to said intelligence-transmission conductor, said railway circuit comprising a trolley conductor and a track, and means for inductively interlinking the conductors of said feeder circuit and the trolley

conductor with said track in order that the return flow of the trolley currents, as well as ground currents from the feeder circuit, may be confined to said track in preference to the earth.

15

In testimony whereof, I have hereunto subscribed my name this 23rd day of Oct., 1917.

ALMON W. COPLEY.
